[57] CLAIM

The ornamental design for a golf club head cover, as shown and described.

DESCRIPTION

FIG. 1 is a perspective of the golf club head cover showing my new design;

FIG. 2 is a back elevation of the golf club head cover; FIG. 3 is a front elevation of the golf club head cover; and

FIG. 4 is a side elevation of the golf club head cover, the other side elevation being a mirror image of this side.

FIG. 1

FIG. 4

FIG. 3

FIG. 2
